UNITED STATES PATENT OFFICE.

JOHN JACKSON, OF CLINTON, IOWA, ASSIGNOR TO JOHN ALBERT LUBBERS AND CHARLES LEONARD BELL, OF CLINTON, IOWA.

FLY-SWATTER.

1,124,138.

Specification of Letters Patent.

Patented Jan. 5, 1915.

Application filed November 4, 1912. Serial No. 729,430.

To all whom it may concern:

Be it known that I, JOHN JACKSON, a citizen of the United States, residing at Clinton, in the county of Clinton and State of Iowa, have invented new and useful Improvements in Fly-Swatters, of which the following is a specification.

This invention relates to fly killers or swatters, and the primary object of the same is to provide a cheap device of this class having an effective spring action and wherein the organization is simple and strong and durable, the main body of the killer or swatter being reinforced against breakage both through the medium of a spring device centrally engaging the same and a flexible edge binding having a tendency to restore the body of the device to normal position after use and conjointly operating with the spring to produce a quick return of the body to its position relatively to the handle and thereby materially reduce the strain on the spring.

With these and other objects and advantages in view, the invention consists in the construction and arrangement of the several parts which will be more fully described and claimed.

In the drawing:—Figure 1 is a perspective view of the killer or swatter embodying the features of the invention. Fig. 2 is a plan view of the same partially broken away. Fig. 3 is a transverse vertical section taken in the plane of the line 3—3 in Fig. 2. Fig. 4 is a view similar to Fig. 3 showing a slight modification in the form of the spring.

The numeral 5 designates the wire gauze body of suitable mesh and dimensions having a rear rounded or semicircular extremity 6. A binding 7 of suitable flexible material preferably imitation leather, is applied and secured fully around the edges of the body 5, such binding strip being attached to the body 5 by means of stitches or other suitable fastenings passing through the reticulations of the body. A handle 8, of suitable length, is provided with the horizontal slot or kerf 9 at its inner end, and into the said slot or kerf 9 the rear portion of the body, including the binding 7 thereover, is pushed into the said slot and secured by fastening pins or small nails 10 driven through the handle and the rear central portion of the body 5.

In the form of the device shown in Figs. 1, 2 and 3, a doubled spring 11 is looped through the central portion of the body 5 at its rear extremity within the handle slot or kerf 9 just ahead of the innermost fastening 60 pin or nail 10, the rear extremity of the spring being doubled or looped through the center of the body, and at its outer extremity the said spring also embraces a portion of the wires of the body, as at 12, and is 65 secured, the one spring member 11^a being disposed out of alinement with relation to the remaining member, as clearly shown by Fig. 2, so as to give them a converging contour toward the outer extremity of the 70 spring.

The lateral projection of the spring member 11^a relatively to the remaining spring member also gives a greater width of spring bearing and greater spring resistance on 75 the opposite sides of the wire gauze body 5 adjacent to the end of the handle 8 extending over and engaging the body, so that the body is strengthened against breakage adjacent to the handle end. Moreover, the 80 rear doubled or bent extremity of the spring is inserted in the kerf or slot 9 of the handle and ahead of the fastenings 10 and directly engages the opposing walls of the kerf or slot 9 and is firmly secured without being in the least weakened by penetrating fastenings. The advantage of this spring structure is that the body 5 is 85 centrally stiffened at the point most desirable to resist breakage and to return the 90 said body to normal position after use, and the particular arrangement of the two parts of the spring on opposite sides of the body gives a more positive spring action. The 95 spring 11 constructed and arranged as just explained is auxiliated in its action by the flexible binding 7, the latter not only covering and protecting the raw edge, so to speak, of the body 5, but also operating to keep the said body in shape, and thereby making 100 a stronger and more durable striking or swatting body. By arranging the spring at its rear extremity within the handle and looping it through the body 5, there is less liability of splitting the handle in applying 105 the same through the medium of the single fastenings or nails 10, the usual custom being to drive a double-pointed nail or staple through the handle to hold the rear part of the body in fixed relation to the handle, and 110

said double-pointed fastening frequently splits the handle, with material loss in the manufacture and disadvantage in the service of the killer or swatter.

5 In the form of the device shown by Fig. 4, a single spring 13 is used and secured at its opposite ends to the wire gauze body 5, as shown. It is preferred, however, that the double form of spring shown by Figs. 10 1, 2 and 3 be used.

15 The improved killer or swatter will be found exceptionally advantageous, and it will be understood that changes in the proportions, dimensions and minor details may 20 be resorted to without departing from the spirit of the invention.

What is claimed is:

20 A fly swatter having a wire gauze body, a flexible binding material extending around the entire edge of the body, a handle having a slotted end in which the rear central portion of the body and the binding are tightly inserted, fastening means extending through the slotted end of the handle and body, and 25 a flat spring doubled its full length and ex-

tending longitudinally of the body from an intermediate point and having the two members thereof loosely bearing against opposite sides of the wire gauze body, the bends at the front and rear extremities of the flat spring being passed through the said body and the rear bent end inserted in and bearing against the walls of the slot of the handle ahead of the said fastening means and thus secured without penetrating the spring 30 by the fastening means, the members of the doubled spring being laterally extended relatively to each other toward the handle to increase the spring bearing near to the handle and strengthen the body against 35 breakage adjacent to the forward handle end engaging the body.

40 In testimony whereof I have hereunto set my hand in presence of two subscribing witnesses.

JOHN JACKSON.
